UNITED STATES PATENT OFFICE.

JOSEPH GOULDBURN AND WILLIAM THOMAS BUCKINGHAM ROBERTS, OF LEISCTER, ENGLAND, ASSIGNORS TO UNITED SHOE MACHINERY CORPORATION, OF PATERSON, NEW JERSEY, A CORPORATION OF NEW JERSEY.

MACHINE FOR CONFORMING UPPERS TO LASTS.

Application filed November 4, 1926, Serial No. 146,264, and in Great Britain November 24, 1925.

This invention relates to machines for use in the manufacture of shoes for conforming uppers to the shape of their lasts, and has for one of its principal objects to provide in upper-conforming machines of the pulling-over machine type improvements relating to operations upon the upper farther rearwardly than has been the practice heretofore in the use of pulling-over machines,—for example, 5 in locations where the edge of the shoe bottom curves inwardly toward the shank at the rear of the ball line.

It is the usual practice in the manufacture of most of the well-known types of shoes to 15 subject the upper, after the pulling-over operation and prior to the side-lasting of the shoe, to an operation known as waist-pulling, whereby the upper is pulled and fastened to the insole in locations considerably at the rear 20 of those where the side grippers of the pulling-over machine engage it, usually just at the rear of the ball line where the edge of the shoe bottom curves inwardly toward the shank. This operation is regarded as desirable, especially on high-class work, in order 25 to guard against the accumulation at any point of undue fullness in the upper, with consequent wrinkling, when the side-lasting operation is performed by the use of a lasting 30 machine of the step-by-step type, and also to assist in conforming the upper tightly and smoothly to the contour of the last over the instep and in the shank. This separate waist-pulling operation is usually performed manually 35 by the use of hand pincers, first at one side of the shoe and then at the other side, although under some conditions it may be performed by the use of the side lasting machine before the machine is used in the customary manner to last the shoe progressively 40 along the sides.

It is an object of this invention to provide means for performing the waist-pulling operation in the pulling-over machine, thus 45 eliminating the necessity for a separate waist-pulling operation between pulling-over and lasting. There is accordingly herein disclosed a novel organization of means for pulling an upper over the forepart of a last and for pulling it also and fastening it adjacent to the ends of the ball line, substantially 50 in the locations where the edge of the shoe bottom curves inwardly toward the shank. It is considered preferable that the pull near the

ends of the ball line shall not take place until 55 after the upper has been pulled at the forepart, and the invention accordingly provides an organization whereby the different upper-pulling operations are automatically timed to take place in this sequence. 60

In accordance with a further very desirable feature of the invention, the operator of the pulling-over machine is relieved of the necessity of exercising more care or of spending more time than customary in presenting 65 the work to the machine and arranging the upper in the gripper jaws, notwithstanding the addition to the machine of the waist-pulling grippers. To this end, advantage is taken 70 of the fact that the waist-pulling grippers, as above explained, do not apply their pull to the upper until after the upper has been tensioned by the main pulling-over grippers, the waist-pulling grippers being so arranged that the margin of the upper is introduced 75 between their open jaws by the pull of the main side grippers. In the construction shown, moreover, the waist-pulling grippers are so mounted as to be yieldingly movable heightwise of the shoe in response to engagement 80 of the margin of the upper therewith as the upper is pulled by the main grippers, so that before they operate upon the upper they assume positions determined by the extent of the pull first applied at the fore- 85 part.

When the waist-pulling operation is performed in the pulling-over machine, it is found that the stretching of the upper effected by the main grippers in their updraw 90 movement (i. e., their movement heightwise of the last) is such that it is sufficient for the waist-pulling grippers to operate with overdraw movements only, thereby simply pulling the upper inwardly over the insole 95 and laying it thereon in position to be fastened. The invention, therefore, further provides for imparting to the waist-pulling grippers, as distinguished from the main grippers, movements only in directions generally widthwise of the last. Conveniently also, the waist-pulling grippers may be so constructed and arranged as to extend generally widthwise of the last, while the main grippers extend, as usual, in directions substantially 100 heightwise of the last. In the construction herein shown, moreover, the waist-pulling grippers are so mounted that, as they are 105

5 moved inwardly over the bottom of the last, they are permitted to approach the plane of the last bottom in response to resistance of the upper to the inward pull of the grippers thereon, so that they lay the margin of the
10 upper upon the bottom face of the insole; and provision is afforded also for turning movement of the gripper jaws into positions approximately parallel to adjacent portions of the edge of the shoe bottom at the rear of the ball line simultaneously with their inward pulling movement, to assist in laying the upper evenly over the edge of the insole. Preferably, as shown, the means for moving
15 these grippers inwardly over the insole is yieldable in response to resistance of the upper when the upper has been subjected to a predetermined stress, so that the grippers assume positions determined by the particu-
20 lar shoe in accordance with the stress of the upper.

The invention further provides novel means for fastening the upper in the waist-pulling locations, comprising fastening devices that
25 are positioned relatively to the shoe by the movement of the grippers, the construction shown comprising tack-driving devices that are carried by the grippers. In order to insure that the fastening devices will be properly effective to fasten the upper, the grippers herein shown, while yieldable toward the plane of the shoe bottom as above explained, are locked against yield in the opposite direction at the time of the fastening operation.
30 It will be evident that, with the grippers positioned relatively to the shoe in accordance with the stress of the upper, as above described, the fastening devices are likewise so positioned; and in one form of the invention the fastening means is rendered operative to drive the fastening in response to resistance of the upper to the inward movement of the gripper.

While the invention thus has principally
45 in view improvements relating to what is termed a waist-pulling operation, it is considered that in the provision of upper-pulling and fastening means such as disclosed the invention presents various novel and useful features irrespective of the particular location upon the shoe where the operation in question is performed, and it is the intention to claim the invention thus broadly. The invention is illustrated, by way of example,
50 in its application to a well-known type of pulling-over machine the characteristic features of which are shown and described in United States Letters Patent No. 1,510,851, granted on October 7, 1924, upon an application of Arthur E. Jerram and Joseph Gould-
55 bourn, and in earlier Letters Patent therein mentioned; but it is to be understood that it is not limited to machines of that particular type.

60 65 The above-mentioned and other features of

the invention, including various novel details of construction and combinations of parts, will now be more particularly described by reference to the accompanying drawings and pointed out in the claims.

70

In the drawings,

Fig. 1 is a view in side elevation of a machine of the type illustrated in the above-mentioned Letters Patent, with the present invention embodied therein, parts of the machine being shown diagrammatically and parts omitted for the sake of clearness;

Fig. 2 is an enlarged detail view, in side elevation, of portions of the structure shown in Fig. 1, comprising the waist-pulling mech-
75 anism at one side of the machine;

Fig. 3 is a detail perspective view of portions of the structure shown in Fig. 2 and associated parts;

Fig. 4 shows one of the waist-pulling mech-
85 anisms and associated parts as viewed in the direction of the arrow A of Fig. 1 by an observer at the rear of the machine;

Fig. 4^a is a view similar to a portion of Fig. 4, but illustrating a different position
90 of the waist-pulling gripper;

Fig. 5 is a view from the rear at right angles to Fig. 4;

Figs. 6 and 7 are views corresponding substantially to Figs. 4 and 5 respectively, but
95 showing an alternative construction;

Fig. 8 is a section on the line VIII—VIII
of Fig. 7;

Fig. 9 is a section on the line IX—IX of
100 Fig. 6; and

Figs. 10 and 11 are views further illustrating, with reference to a shoe, different operating positions of the waist-pulling grippers.

As fully shown and described in the above-mentioned Letters Patent, the pulling-over machine illustrated comprises in its general organization a toe gripper B and opposite side grippers C (Fig. 4) which are operated to pull an upper over a last positioned bottom downward upon a sole rest D. It will be
110 understood that these grippers, which engage the upper at the end of the toe and at the sides of the forepart at or near the ends of the tip seam, are operated automatically by power-driven means to grip and pull the
115 upper heightwise of the last upon the starting of the machine, and that the machine then comes to a stop with the upper held under tension. When the machine is again started the grippers are operated to draw the upper
120 inwardly over the insole and the margin of the upper also is wiped inwardly over the insole and is fastened by tacks driven upwardly through the upper and into the insole
125 at the end of the toe and the sides of the forepart. Portions of the overwiping and fastening devices are shown at E.

For purposes of the present invention there is provided at each side of the machine, at the rear of the side grippers C, a waist-pulling
130

gripper for pulling the upper at or near the end of the ball line, preferably at that portion of the shoe where the edge of the shoe bottom curves inwardly toward the shank, together with means for fastening the upper in that location. The drawings show in detail the waist-pulling mechanism at the left-hand side only of the machine, since it will be understood that the corresponding mechanism at the other side of the machine will be similarly constructed and arranged. This waist-pulling mechanism, indicated generally at F (Fig. 1), is mounted indirectly, as will more fully appear, upon a bracket 11 which is pivoted upon a stud 13 on the frame of the head of the machine so that by adjusting the bracket about the stud the position of the mechanism lengthwise of the shoe may be varied. The bracket 11 is provided on one side with a lug 15 (Fig. 2) which underlies a retaining plate 17 that acts both to prevent the bracket from springing outwardly, widthwise of the shoe, and also to clamp the bracket in adjusted position. If desired, the bracket may be further guided and held by similar means (not shown) located on the opposite side thereof from the lug 15. Any suitable means also may be provided, if desired, for adjusting the brackets 11 at the opposite sides of the machine, either simultaneously or individually, to position the opposite waist-pulling mechanisms differently for operating upon right and left shoes.

Mounted on the bracket 11 is a floating gripper-supporting bracket 41 (Figs. 2, 4 and 5) provided on one side with a pivot stud 43 which fits in a hole formed in an extension 21 of the bracket 11; and an arcuate rib on the bracket 41, concentric with the hole, underlies a corresponding rib on the bracket 11 and assists in guiding the bracket 41 as it moves about the axis of the pivot stud 43. The axis of the stud 43 extends generally parallel to the longitudinal median line of the shoe. A plate 45 (Fig. 4) is pinned to the arcuate rib of the floating bracket 41 and overlaps the other arcuate rib and the pivot stud 43 and thus keeps the floating bracket in place. A forked link 47 (Fig. 5) is pivoted at one end to the floating bracket 41 and at its other end extends through a part of the bracket 11, this link having on its outer end nuts 48 to limit its movement under the action of a compression spring 49 which surrounds the link and tends always to separate the two brackets. The floating bracket 41 may thus not only be adjusted bodily, with its gripper, lengthwise of the shoe by the above-described adjustment of the supporting bracket 11 about its pivot 13, but may also have a short rocking movement relatively to the bracket 11 about the axis of the pivot stud 43 to permit the gripper to assume different positions heightwise of the shoe.

On the opposite side of the floating bracket

41 from the pivot stud 43 there is formed a rectangular slideway (Fig. 2) in which is mounted a gripper jaw carrier 51 formed with a shoulder 53 (Figs. 4 and 5) for engagement with a shoulder on the floating bracket to limit outward movement of the jaw carrier away from the shoe. In order to assist the slideway in holding the jaw carrier 51 from springing downwardly in the operation of the fastening means (hereinafter described), the floating bracket 41 is provided with a projection 55 (Fig. 5) which underlies that portion of the jaw carrier 51 which projects outside of the slideway.

The inner end of the jaw carrier 51 is bored to receive a pivot stud 57 depending from an inner jaw 59 of the waist-pulling gripper. This jaw is provided with an outwardly extending tail portion 60 (Fig. 5) which is held in place at its outer end by being located in a recess 61 in the carrier 51, but is free to swing with the jaw 59 about the axis of the stud 57. Co-operating with the inner jaw 59 is an outer jaw 63 which has a depending rib 65 mounted for sliding movement in a parallel-sided slot extending lengthwise of the tail 60 of the inner jaw, the arrangement being such that the outer jaw can slide toward and from the inner jaw upon the tail 60 but not laterally thereof. In order to hold the outer jaw 63 slidably in place, its rib 65 is fixed to a slide 67 which extends through a slot 69 (Fig. 4) in the jaw carrier 51 and is fastened to a cover plate 71 underneath the jaw carrier. The slot 69 is so formed that it not only permits the slide 67 and the outer jaw to move longitudinally of the carrier 51, or widthwise of the shoe, but also permits both jaws to be swung with the tail 60 about the pivot 57, as will hereinafter more fully appear.

In order to provide for the operative movement of the waist-pulling gripper jaws, the carrier 51 is slotted longitudinally to form a guideway for a jaw actuator 73 (Figs. 2 and 5), the inner end portion of which is arranged to contact with a projection 75 on the outer jaw 63 and force the jaw inwardly toward the jaw 59. The actuator 73 is provided with a shoulder 74 to engage the carrier 51 and thereby limit outward movement of the actuator away from the shoe.

The slideway for the carrier 51 in the bracket 41 is provided with a cover 77 (Fig. 4) having thereon a lug 79 on which is mounted a carrier-holding pawl 81 arranged to engage teeth 83 on the carrier 51 to hold the latter with the inner jaw 59 at times against outward movement, the tail 85 of the pawl being engaged by a spring to hold the pawl in operative position. The pawl 81 has fixed thereon an offset arm 87 the end of which extends into the path of a member 89 which moves at the correct time to lift the pawl from engagement with the teeth 83 and thus permit the

inner jaw to move outwardly, the member 89 being a portion of the mechanism provided for transferring tacks to the side tacker arms, as more fully described in the Letters Patent 5 mentioned. The arrangement is such that the inner jaw 59 is not released by the pawl until after the outer jaw 63 has been retracted from the inner jaw by the pull of a lug 76 on the actuator 73 upon the projection 75 10 of the outer jaw, and has thus released the upper.

The jaw actuator 73 carries a bent rod 91 which is connected by a tension spring 93 to a hook 95 on the jaw carrier 51, so that after the 15 inward pulling or overdrawing of the upper by the waist-pulling gripper has been completed, and while the outer jaw 63 is being returned to its outer position, the spring 93 is tensioned by reason of the fact that the carrier 51 is held by the pawl 81 from being retracted. When the pawl 81 thereafter releases the carrier 51, the spring 93 serves to 20 retract the carrier with its jaw 59 to the position determined by engagement of the shoulder 53 with the bracket 41, the jaw 59 being then spaced from the jaw 63 sufficiently to 25 permit the margin of the upper of the next shoe to be introduced between the jaws. In order that the spacing of the jaws may be 30 varied, a stop 42 is screwed into the bracket 41 and is adapted to contact with the outer end of the carrier 51, so that by adjusting the stop the carrier can be positioned with its shoulder 53 out of engagement with the 35 bracket 41 and at different distances therefrom. It will be understood that the spring 93 is always in tension, and in gripping the upper the stress of the spring is reduced as the outer jaw 63 is moved inwardly under 40 control of the actuator 73 until the upper is gripped by the force of the spring, after which both jaws are moved inwardly to pull the upper by continued movement of the actuator 73 in engagement with the outer jaw.

The actuator 73 is operated to cause the waist-pulling gripper jaws to close upon the upper and to pull the upper inwardly over the insole by connection with the means whereby, after the pulling of the upper by the 45 main grippers B and C, inward movement toward the shoe is imparted to the usual side tacker arms of the pulling-over machine, which carry the means, indicated generally at E (Fig. 4), for wiping the upper inwardly 50 and for fastening it by the use of tacks. This means includes the usual side trip spring casing 101 (Fig. 3) which receives its operative movement, at the beginning of the second stage of the cycle of the machine, from mechanism of the well-known type illustrated and 55 is yieldingly connected in a well-known manner with one of the side tacker arms, a portion of which is shown at 102. The casing 101 is provided with an extension 103 having 60 therein a slot 105 in which is located a

roll 107 mounted on one arm of a bell-crank lever 109 pivoted on the frame of the machine. The other arm of the lever 109 has rotatably mounted therein a shackle 111, pivoted in the forked end of which is a block 113, and 70 through a hole in the block 113 extends one end of a rod 115 which is gripped between two pins 117 extending through the block 113 and held toward the rod by a U-shaped spring 119. The other end of the rod 115 is mounted to 75 slide through a pin 121 which is pivotally mounted in a shackle 123 (Figs. 4 and 5), the shackle 123 being pivoted in one arm of a bell-crank lever 125 carried by the bracket 11. A compression spring 127 is mounted on the rod 80 115 between the bell-crank lever 125 and a nut 128 on the rod to transmit movement of the bell-crank lever 109 to the lever 125. Means indicated generally at 129 are provided for adjusting the strength of the spring 127, so 85 that there shall be no oversretching of the upper. The arrangement is such that the spring 127 yields when the tension of the upper reaches the amount for which the spring is adjusted, the rod 115 then sliding through 90 the pin 121 as the bell-crank lever 109 continues its movement. The pin 121 has a projecting nose 131 (Fig. 4) for a purpose hereinafter described. The second arm of the bell-crank lever 125 is provided with a slot 95 133 (Fig. 5) in which is located a roll 135 carried by the actuator 73 for connecting the lever to the actuator.

The projection 75 of the outer jaw 63 which is engaged by the inner end portion of the actuator 73 to force the jaw inwardly is inclined to the direction of movement of the actuator, as illustrated in Fig. 4, so that the pressure of the actuator thereon tends to swing the tail 60 of the inner jaw 59 toward the heel 100 end of the shoe; and the slot 69 in the carrier 51, through which the slide 67 extends, is so shaped as to permit such swinging movement to take place while the jaws are being 105 operated to pull the upper inwardly over the insole. It will be understood that by reason of the connection between the inner and outer jaws, both the jaws will thus be swing together, as illustrated in Fig. 4^a, so that the jaws receive a twisting movement in a direction to cause them to assume a position approximately parallel to the adjacent edge of the shoe bottom at the rear of the ball line. On the return movement of the jaws they are 110 swung back automatically to their original 115 position by the action of the lug 76 on the inner inclined face of the projection 75.

Since the waist-pulling gripper jaws are not operated to grip and to pull the upper until that time in the cycle when the side tacker arms are swung inwardly after the pulling of the upper by the main grippers, as hereinbefore explained, it will be evident that when the upper is pulled by the main side grippers C, the jaws of the waist-pulling 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 grippers are open; and the arrangement is such that the margin of the upper is introduced into the waist-pulling grippers by the action of the main grippers, thus relieving the 5 operator of the necessity of giving any special attention to the waist-pulling grippers in presenting the work to the machine. As hereinbefore described, the bracket 41 may swing about the axis of the pivot stud 43 against 10 the resistance of the spring 49, to cause the waist-pulling gripper jaws 59 and 63 to move downwardly in a direction away from the shoe bottom. Such movement of the jaws will take place in response to engagement of 15 the margin of the upper with the tail 60 of the inner jaw 59 when the upper is pulled by the main pulling-over grippers B and C before the waist-pulling grippers are closed thereon. In their initial positions the waist-pulling grippers are located below the margin 20 of the upper, but at a higher level than that to which the margin will be pulled by the action of the main pulling-over grippers. The taut edge of the upper will, therefore, enter 25 the open waist-pulling gripper jaws and will swing the jaws downwardly to positions determined by the extent of the main pull of the side grippers, so that the waist-pulling grippers will be automatically adjusted to 30 the correct heightwise position for subsequently gripping the upper.

It is desirable that after the waist-pulling grippers have been correctly adjusted to the proper heightwise position by the action of 35 the margin of the upper thereon, they shall be restrained from subsequent movement in a direction away from the plane of the shoe bottom, especially when the fastening mechanism associated therewith is operated to 40 fasten the upper in the manner hereinafter described. Accordingly the bracket 41 has pivoted thereon a pawl 141 (Fig. 5) which is pressed by a spring 143 into engagement with teeth 145 formed on a block 147 fixed to a 45 wing extending from the bracket 41. The pawl 141 carries an extension 149 arranged to be engaged by the nose 131 of the pin 121, so that when the bell-crank lever 125 is rocked to close the jaws and move them inwardly 50 over the shoe bottom, it releases the pawl 141 for engagement with the teeth 145 so as to lock the bracket 41 from downward rocking movement. The pawl, however, does not prevent the waist-pulling gripper from moving 55 up toward the shoe bottom as it is operated to pull the upper inwardly over the insole, and such movement will ordinarily take place in response to the pull of the upper thereon, so that the gripper will act to lay the upper 60 upon the bottom face of the insole. When the bell-crank lever 125 is moved in the opposite direction, the nose 131 strikes the extension 149 of the pawl 141 and disengages the pawl from the teeth 145. For greater precision the pawl 141 is duplicated, the second

tooth-engaging edge being half a tooth in front of the first.

It will be understood that each of the waist-pulling grippers will be initially adjusted into proper position to receive the margin of the upper by manipulation of the nuts 48 and by adjustment of its supporting bracket 11 about the pivot 13. The jaws of each waist-pulling gripper are, moreover, initially very much wider apart than the main gripper jaws, in order to insure that the margin of the upper will be pulled into position between them by the action of the main jaws.

For fastening the upper after it has been pulled by each waist-pulling gripper, there are mounted on the movable cover plate 71 under the jaw carrier 51 two ears, one of which is shown at 151, having therein slots 153 which provide a guideway for a driver bar carrier 155 to which is secured a tack 70 driver 157. The driver 157 is arranged to operate in an orifice or tack pocket 159 formed in the outer jaw 63 to which a tack is delivered from above by mechanism not herein shown but similar to that provided for delivering tacks to the main tacking devices. For operating the driver 157, a toggle arm 161 is pivoted to the ears 151, another toggle arm 163 is pivoted to the driver bar carrier 155, and the two toggle arms are pivoted together on a pivot member 165. The toggle arms are mounted between the ears 151 and are conveniently composed of duplicate links. The pivot member 165 has a shank provided with a quick thread for engagement with a ball-ended nut 167 held in a spherical socket formed in the ears 151, so that when the nut is turned in one direction the toggle is straightened and the driver 157 operated to drive a tack, and when it is turned in the 80 opposite direction the driver is retracted. The nut 167 has a socket in which is fixed one end of a flexible shaft 171 (Fig. 1). It will thus be evident that the tack driver and its operating connections to the flexible shaft 85 171 move with the jaw 63 toward and from the jaw 59 and also swing with the jaws about the axis of the stud 57, so that the location of the tack is determined by the position of the 90 gripper.

For rotating the flexible shaft 171, first in one direction and then in the other, it is connected to mechanism with which machines of the illustrative type are provided for retracting or coocking the main driver bars after the 100 driving of the pulling-over tacks. It will be understood that this well-known mechanism, a portion of which is shown in Fig. 3, is pivoted at 175 on the frame of the machine for operative swinging movement, and comprises 105 at each side of the machine a driver bar retracting plate (not shown). For the purposes in view, there is pivoted also at 175 a bent lever 173, the upper end of which is secured 110 at 177 to a portion of the above-mentioned 115 120 125 130

driver bar retracting mechanism, preferably to the driver bar retracting plate located at the same side of the machine. The other end of the lever 173 is pivoted to a rod 179 having rack teeth 181 formed thereon which engage gear teeth 183 cut in the shaft 185. The rod 179 is slidably mounted in a casing 187 which is pivoted on the shaft 185. The end of the shaft 185 is fixed to the lower end of the flexible shaft 171, and when the above-mentioned driver bar plate is swung upwardly about its pivot 175 preparatory to the lowering or retracting of the main driver bars, the flexible shaft 171 is rotated in one direction to operate the driver bar carrier 155 of the waist-pulling mechanism. When the plate receives its downward movement to retract the driver bars, the flexible shaft is turned in the opposite direction to retract the carrier 155. It will thus be seen that the tacks for fastening the upper in the waist-pulling locations are not driven until after the main pulling-over tacks have been driven, but preferably before the shoe is released by the means (not shown) which supports it against the pressure of the tack drivers.

In order to provide for the introduction of the hereinbefore described waist-pulling mechanism into the machine, the usual tip-straightening mechanism is removed and the support of the shoe rest D is somewhat altered in shape to provide suitable clearance for the additional grippers. Any convenient construction of tip-straightening mechanism may be used, in a different position, in place of that removed; for example, one such as is disclosed in Letters Patent No. 1,656,365, granted on January 17, 1928 upon an application of Robert H. Silvester and Arthur

40 Bates.

The waist-pulling mechanism at the opposite side of the machine, including the gripper and the fastening means, will preferably be identical with that herein described, except for such constructional alterations as may be necessary to adapt it to the different position in the machine. There will, however, be no need of duplicating the mechanism for rotating the tack-driving shaft 185, since that shaft may extend to both sides of the machine and may have a flexible shaft 171 coupled to each end of it.

In the operation of the machine, after the opposite waist-pulling mechanisms have been 55 adjusted in the manner described to position them in proper relation to the size and style of shoe on which the machine is to operate, and it may be also to adapt them to the particular requirements of a right or a left shoe, the operator presents the shoe to the machine in the usual manner, positioning the margin of the upper within the main pulling-over gripper jaws B and C without giving any particular attention to the relation of the upper 60 to the waist-pulling gripper jaws. The

machine is then started, and the main grippers are operated to tension the upper at the end of the toe and the sides of the forepart, whereupon the machine comes automatically to a stop. In this operation the margin of the upper, as it is pulled downwardly by the grippers, engages the tail 60 of each of the inner waist-pulling gripper jaws and thus rocks both the waist-pulling grippers downwardly to position them in accordance with the extent of the pull applied to the upper at the sides of the shoe. While the machine is at rest after thus pulling the upper, the operator is enabled to straighten the tip as may be required, before the waist-pulling grippers have gripped the upper, by manipulation of the tip-straightening mechanism in the well-known manner. In the next or final stage of the cycle of the machine, at the time when the side tacker arms 102 are swung inwardly toward the shoe to lay the margin of the upper over the insole, the bell-crank levers 125 are operated in the manner described to close the waist-pulling gripper jaws upon the upper and to cause these grippers to pull the upper inwardly over the insole. By the movement of the bell-crank levers 125 the pawls 141 are released to permit them to lock the waist-pulling grippers from movement away from the plane of the shoe bottom; and at this time also the carrier-holding pawls 81 are in engagement with the teeth 83 on the jaw carriers, so that as the latter are moved inwardly they will be locked in their innermost positions. During the inward movements of the waist-pulling grippers they will rock about the pivot studs 43 of the floating brackets 41 in response to the pull of the upper upon the gripper jaws, so that the jaws will approach the plane of the insole and will lay the upper upon the bottom face of the insole, as illustrated in Fig. 11. The jaws will also be swung about their pivots 57 by the action of the actuators 73 thereon in the manner hereinbefore described, so that they will twist the margin of the upper and will assume positions more nearly parallel relation to the adjacent portion of the edge of the shoe bottom where the edge curves inwardly toward the shank. The springs 115 127 will, as a rule, yield to prevent the upper from being over-stretched, and if necessary the friction grip of the pins 117 on the rods 115 will also yield.

After the upper has thus been pulled inwardly by the waist-pulling grippers, and also after the main pulling-over tacks have been driven, the tacks in the waist-pulling locations are driven in the manner hereinbefore described. Thereafter the return movements of the trip-spring casings 101 will first retract the outer waist-pulling gripper jaws to release the upper, the inner jaws being still held by the pawls 81. In the return movement of the bell-crank levers 125

the pawls 141 are retracted, thereby releasing the waist-pulling grippers for downward movement in operating upon the next shoe. Near the end of the cycle the carrier-holding pawls 81 may likewise be retracted from the teeth 83 to permit the inner jaws to be moved outwardly by the springs 93, or by a suitable arrangement of means for operating the arms 87 of the pawls this action may be delayed 5 until in a new cycle of operations the tensioning of the upper by the main pulling-over grippers has at least begun.

If it is not desired that the waist-pulling grippers be swung to cause their upper-gripping faces to assume positions approximately parallel to the adjacent edge of the shoe bottom, an organization somewhat more simple than that hereinbefore described may be utilized, and such an organization is shown 10 in Figs. 6 to 9, inclusive. The waist-pulling mechanism of the alternative construction is mounted indirectly upon a bracket 211 similar to the bracket 11 of the construction first described and similarly adjustable. A floating bracket 241 is provided one one side with a pivot stud 243 (corresponding to the stud 43 of the construction first described) which is mounted to turn in a hole in the bracket 211. On the opposite side of the bracket 241 from 15 the pivot stud 243 there is formed a rectangular slideway in which is mounted for longitudinal movement an inner jaw carrier 251 having at its inner end a jaw 253 and at its outer end a shoulder arranged to contact with an adjustable screw stop 245 on the bracket 241, so that this stop limits the outward movement of the inner jaw. The inner end portion 20 of the jaw carrier 251, which projects from the bracket 241, is provided with a slot 260 through which there projects a rib forming a portion of an outer jaw 261, a cap plate 263 being attached to the rib in order that the outer jaw may be kept in place on the inner jaw carrier in its sliding movement toward 25 and from the inner jaw.

For moving the outer jaw 261 toward and from the inner jaw 253, and for moving both jaws widthwise of the shoe to pull the upper, there is provided a jaw actuator 273 which is located, with the inner jaw carrier, in the rectangular slideway in the floating bracket 241 and can slide longitudinally therein. The inner end of the actuator 273 is provided with a hook 275 which engages a hook 265 on the outer jaw 261. The outer end of the actuator 273 is provided with a guideway 277 (Fig. 9) in which is located a slide 279 normally held from moving relatively to the actuator, one end of the slide 279 having a lateral extension 281 (Fig. 8) projecting through a slot in the side of the actuator. The extension 281 carries a spherically-surfaced pin 283 connected by a link 285 to one end of a bell-crank lever 287 which 30 is mounted and operated similarly to the

bell-crank lever 125 of the construction first described, with the exception that there is no provision for yield in the operating connections.

In order that there shall be no over-stretching of the upper, the slide 279 is adapted to move relatively to the actuator 273 along the guideway 277 when the upper has been subjected to a predetermined degree of tension. The actuator 273 carries a lug 280 and a wing 282, both of which members extend through slots in the inner jaw carrier 251 and the floating bracket 241. Mounted in the wing 282 is a poppet or plunger 284 having a beveled end adapted to enter a complementally shaped recess in the slide 279 so as normally to hold the slide stationary relatively to the actuator 273. Pivoted on the lug 280 is a driver arm 291 having fast thereon a second arm 293 to which is pivoted one end of a bar 295 that is pivoted at its other end to a rod 297 extending upwardly through the actuator 273. The rod 297 carries a semi-spherical washer 299 seated in a recess in the actuator 273 and held thereagainst by a spring 301 the tension of which may be adjusted by a nut 303 on the rod 297. The bar 295 engages the outer end of the plunger 284 and thereby holds the latter 35 yieldingly in engagement with the slide 279, as illustrated in Fig. 9.

The driver arm 291 carries a driver 292, and when the driver is cocked, or in retracted position, a shoulder 305 on the bar 295 is in engagement with a co-operating lip 307 on the wing 282, so that the bar 295 acts as a latch to hold the driver retracted. When the bell-crank lever 287 has moved the jaw actuator 273 to grip and to stretch the upper with the required force, further movement of the lever 287 causes the slide 279 to move relatively to the actuator 273 by reason of resistance of the upper to further inward movement of the gripper, the beveled face of the plunger 284 sliding upon the sloping face 40 of the recess in the slide 279. This causes the plunger to swing the bar 295 sufficiently to release the shoulder 305 from the lip 307, whereupon a spring 309 located between the wing 282 and the arm 293 swings the latter 45 about its pivot and causes the driver 292 to drive a tack. The driver passes through the outer jaw 261 and adjacent parts by means of openings that are tapered to allow for the angularity of the driver movement.

In order to cock the driver 292, the driver arm 291 carries a third arm 311 which, when the bell-crank lever 287 retracts the jaw actuator 273, is carried into engagement with an adjustable stop 313 on the bracket 241, and the driver arm is thereby turned until the shoulder 305 on the bar 295 passes the lip 307, whereupon the shoulder is pulled by the spring 301 into position behind the lip. In the driving movement of the driver 292 the 50

arm 311 is arranged to contact with a stop 312 on the actuator 273 to limit its movement.

A pawl 341 on the bracket 241 co-operates with teeth on a block 347 on the bracket 211 in a manner similar to the operation of the corresponding parts 141 and 147 of the construction first described. A carrier-holding pawl 381 also acts similarly to the previously described pawl 81 to hold the inner jaw 253 in its innermost position against the tension of a spring (not shown but similar in action to the spring 93).

Having described the invention, what we claim as new and desire to secure by Letters

15 Patent of the United States is:—

1. A machine of the class described having, in combination, means for pulling an upper over the forepart of a last, and additional upper-pulling means automatically controlled to operate upon the upper only after it has been subjected to tension by said first-named means and arranged to pull it in a location substantially where the edge of the shoe bottom curves inwardly toward the

25 shank.

2. A machine of the class described having, in combination, means for pulling an upper over a last comprising grippers arranged to grip and pull the upper at the sides of the forepart, additional grippers arranged to grip the upper at the sides of the shoe at the rear of said first-named grippers in locations substantially where the edge of the shoe bottom curves inwardly toward the shank, and automatically controlled means for operating said additional grippers to pull the upper after the upper has been subjected to tension by said first-named grippers.

3. A machine of the class described having, 40 in combination, power-operated means for pulling an upper over a last at the sides of the forepart and for then holding the upper under tension with the machine at rest, and additional power-driven means arranged to operate only after the machine is again started to pull the upper in locations farther rearwardly on the shoe than said first-named means.

4. A machine of the class described having, 50 in combination, pulling-over means comprising grippers arranged to grip and pull an upper at the sides of the forepart and then to hold the upper under tension to permit it to be adjusted on the last, additional grippers arranged to operate on the upper at the rear of said first-named grippers in locations substantially where the edge of the shoe bottom curves inwardly toward the shank, and power-driven means for operating said additional grippers to grip and pull the upper after the upper has been pulled and held for adjustment by the first-named grippers.

5. A machine of the class described having, 55 in combination, grippers for pulling an upper at the sides of the forepart, additional

grippers for pulling the upper in locations farther rearwardly on the shoe than said first-named grippers adjacent to the ends of the ball line, and power-driven means for operating the different grippers in automatically determined sequence to grip and pull the upper first at the sides of the forepart and thereafter to grip and pull it adjacent to the ball line ends.

6. A machine of the class described having, 75 in combination, means for pulling an upper over a last at the sides of the forepart, means for thereafter laying the margin of the upper inwardly over the bottom of the last, and additional means automatically operative in the overlaying operation to pull the upper at the sides of the last in different locations from said first-named means.

7. A machine of the class described having, 85 in combination, means for pulling an upper over a last comprising grippers arranged to operate on the upper at the sides of the forepart, means for thereafter laying the margin of the upper inwardly over the bottom of the last, additional grippers arranged to operate 90 at the rear of said first-named grippers adjacent to the ends of the ball line, and automatic means for operating said additional grippers to grip and pull the upper at the time of the overlaying operation.

8. A machine of the class described having, 95 in combination, means for pulling an upper over the forepart of a last, and additional means automatically controlled to operate upon the upper only after it has been subjected to tension by said pulling-over means to pull it inwardly over the bottom of the last and fasten it in locations where the edge of the shoe bottom curves inwardly toward the shank at the rear of the ball line.

9. A machine of the class described having, 100 in combination, means for pulling an upper over a last by relative movement of said means and the last heightwise of the last, and additional means automatically controlled to 110 operate only after the heightwise pull of said first-named means for pulling the upper in a different location from said first-named means by movement only in a direction substantially widthwise of the last.

10. A machine of the class described having, 115 in combination, a plurality of grippers for pulling an upper over the forepart of a last by relative movement of said grippers and the last heightwise of the last, and additional upper-pulling means comprising 120 grippers arranged to grip the upper in locations adjacent to the ends of the ball line and movable to pull the upper only in directions substantially widthwise of the last.

11. A machine of the class described having, 125 in combination, upper-pulling means comprising opposite side grippers arranged to pull the upper at the sides of the forepart and to have both updraw and overdraw

movements, and additional grippers for pulling the upper adjacent to the ends of the ball line by overdraw movements only.

12. A machine of the class described having, in combination, means for pulling an upper over the forepart of a last by relative movement of said means and the last heightwise of the last, and additional means automatically controlled to operate after the upper has been subjected to tension by said first-named means to pull the upper in locations substantially where the edge of the shoe bottom curves inwardly toward the shank by movements only in directions substantially widthwise of the last.

13. A machine of the class described having, in combination, a plurality of grippers for pulling an upper over the forepart of a last by relative movement of said grippers and the last heightwise of the last, additional grippers arranged to operate upon the upper in locations substantially where the edge of the shoe bottom curves inwardly toward the shank, and automatically controlled means for imparting to said additional grippers movements only in directions widthwise of the last to pull the upper inwardly over the insole after it has been subjected to tension by said first-named grippers.

14. A machine of the class described having, in combination, means for pulling an upper over a last comprising a plurality of upper-gripping and pulling devices arranged to extend generally heightwise of the last in different locations at the end and the sides of the forepart, and additional means for pulling the upper in different locations from said first-named means comprising upper-pulling and gripping devices arranged to extend generally widthwise of the last.

15. A machine of the class described having, in combination, means for pulling an upper over a last comprising a plurality of upper-gripping and pulling devices arranged to extend generally heightwise of the last at the opposite sides of the forepart and mounted for both updraw and overdraw movements, and additional means for pulling the upper adjacent to the ends of the ball line at the rear of said first-named devices comprising upper-gripping and pulling devices arranged to extend generally widthwise of the last and to have overdraw movements only.

16. A machine of the class described having, in combination, means for pulling an upper over a last comprising a plurality of upper-gripping and pulling devices arranged to extend generally heightwise of the last at the opposite sides of the forepart and operatively movable heightwise of the last to pull the upper, and additional devices arranged to pull the upper adjacent to the ends of the ball line and to extend generally widthwise of the last, said last-named devices being movable

in directions substantially widthwise of the last in pulling the upper.

17. A machine of the class described having, in combination, a gripper for pulling an upper over a last, and means for conforming the upper to the last in a different location from said gripper, said conforming means being automatically operative to introduce the margin of the upper into said gripper while the gripper is open to receive it.

18. A machine of the class described having, in combination, different grippers for gripping and pulling an upper over a last in different locations at different respective times, one of said grippers being automatically operative in the upper-pulling operation to introduce the margin of the upper into another gripper before the last-named gripper closes.

19. A machine of the class described having, in combination, means for pulling an upper over a last including a gripper for pulling the upper at the side of the forepart and another gripper for pulling it in a location substantially where the edge of the shoe bottom curves inwardly toward the shank, and controlling means for said last-named gripper constructed to maintain it in position to have the margin of the upper introduced therein by the pull applied by the first-named gripper.

20. A machine of the class described having, in combination, means for pulling an upper over a last including grippers for pulling the upper at the sides of the forepart, additional side grippers for pulling the upper in locations substantially where the edge of the shoe bottom curves inwardly toward the shank, and automatic means for maintaining said additional grippers in position to receive the margin of the upper with their jaws in open condition at the time when the upper is pulled by the first-named grippers and for thereafter closing said additional grippers and operating them to pull the upper.

21. A machine of the class described having, in combination, different grippers for gripping and pulling an upper over a last in different locations at different respective times, one of said grippers being arranged to have the margin of the upper introduced therein by the pull applied by another gripper and being yieldingly movable heightwise of the last, in response to engagement of the margin of the upper therewith, into a position determined by the extent of the pull of said other gripper.

22. A machine of the class described having, in combination, means for pulling an upper over a last including a gripper for pulling the upper at the side of the last adjacent to an end of the ball line, and means for maintaining said gripper in position to receive the margin of the upper, with its

jaws in open condition, while the upper is pulled in a different location by a portion of the pulling means, said gripper being yieldingly movable heightwise of the last in response to engagement of the margin of the upper therewith when the upper is thus pulled.

23. A machine of the class described having, in combination, means for pulling an upper over a last including grippers for pulling the upper at the sides of the forepart, additional grippers for pulling the upper in locations farther rearwardly than said side grippers adjacent to the ends of the ball line, said additional grippers being arranged to have the margin of the upper introduced between their open jaws when the pull is applied by said side grippers and being yieldingly movable heightwise of the last in response to engagement of the margin of the upper therewith as the pull is thus applied, and means for operating said additional grippers to grip and pull the upper after the pull at the sides of the forepart has been substantially completed.

24. A machine of the class described having, in combination, means for pulling an upper over a last, including a gripper for pulling the upper at the side of the forepart and an additional gripper for pulling it in a location farther rearwardly than said first-named gripper adjacent to an end of the ball line, said last-named gripper being arranged to have the margin of the upper introduced between its open jaws by the pull applied by the first-named gripper and being yieldingly movable heightwise of the last, in response to engagement of the margin of the upper therewith, to assume thereby a position determined by the extent of the pull of the first gripper, and means for closing the additional gripper upon the upper and for moving it in a direction substantially widthwise of the last to pull the upper after the pull by the first-named gripper has been substantially completed.

25. A machine of the class described having, in combination, different grippers for gripping and pulling an upper over a last in different locations at different respective times, one of said grippers being arranged to receive the margin of the upper between its open jaws when the upper is pulled by another gripper and being yieldingly movable heightwise of the last in response to engagement of the margin of the upper therewith as the upper is thus pulled, means for operating said yieldable gripper to lay the upper inwardly over the bottom of the last, and means for locking said gripper to prevent it from moving in a direction away from the plane of the last bottom after it has thus laid the upper inwardly.

26. A machine of the class described having, in combination, different grippers for

gripping and pulling an upper over a last in different locations at different respective times including a gripper for pulling the upper adjacent to an end of the ball line, said last-named gripper being arranged to receive the margin of the upper between its open jaws when the upper is pulled by another gripper and being yieldingly movable heightwise of the last in response to engagement of the margin of the upper therewith as the upper is thus pulled, means for moving said ball-line gripper in a direction substantially widthwise of the last to lay the upper inwardly over the bottom of the last, and means for locking said gripper to prevent it from moving in a direction away from the plane of the last bottom after it has thus laid the upper inwardly.

27. A machine of the class described having, in combination, different grippers for gripping and pulling an upper over a last in different locations at different respective times, one of said grippers being arranged to receive the margin of the upper between its open jaws as the upper is pulled by another gripper and being yieldingly movable heightwise of the last in response to engagement of the upper therewith as the upper is thus pulled, said last-named gripper being movable to pull the upper inwardly over the bottom of the last and having upper-fastening means thereon, and means for locking said yieldable gripper against movement away from the plane of the last bottom in the upper-fastening operation.

28. A machine of the class described having, in combination, different grippers for gripping and pulling an upper over a last in different locations at different respective times, one of said grippers being arranged to receive the margin of the upper between its open jaws when the upper is pulled by another gripper and being yieldingly movable heightwise of the last in response to engagement of the margin of the upper therewith as the upper is thus pulled, operating means for moving said yieldable gripper inwardly over the bottom of the last, and a device controlled by said gripper-operating means for locking the gripper against movement in a direction away from the plane of the last bottom.

29. A machine of the class described having, in combination, different grippers for gripping and pulling an upper over a last in different locations at different respective times, one of said grippers being arranged to receive the margin of the upper between its open jaws when the upper is pulled by another gripper and being yieldingly movable heightwise of the last in response to engagement of the margin of the upper therewith as the upper is thus pulled, said yieldable gripper being movable inwardly over the bottom of the last and toward the bottom face of the last to lay the margin of the upper upon the

insole and having upper-fastening means thereon, and automatic means for locking said gripper against movement in a direction away from the plane of the last bottom in the upper-fastening operation.

30. In a machine of the class described, a gripper for pulling an upper over a last, said gripper being arranged to receive the margin of the upper between its open jaws while it is 10 yieldingly movable in a direction away from the plane of the last bottom, means for moving the gripper to carry the margin of the upper inwardly over the bottom of the last, and means for locking the gripper to prevent it from moving in a direction away from said plane after it has thus carried the upper inwardly.

31. In a machine of the class described, a gripper for pulling an upper over a last, said 20 gripper being arranged to receive the margin of the upper between its open jaws while it is yieldingly movable in a direction away from the plane of the last bottom, the gripper being movable inwardly over the bottom of the last 25 and toward the bottom face of the last to pull the upper and lay it upon the insole, and means for locking said gripper to prevent it from moving in a direction away from the bottom face of the last after it has thus laid 30 the upper upon the insole.

32. In a machine of the class described, a gripper for pulling an upper over a last, said gripper being arranged to receive the margin of the upper between its open jaws while it is 35 yieldingly movable in a direction away from the plane of the last bottom, means for operating the gripper to lay the margin of the upper inwardly over the insole, upper-fastening mechanism combined with said gripper to move therewith, and means for locking the 40 gripper to prevent it from moving in a direction away from the plane of the last bottom in the upper-fastening operation.

33. In a machine of the class described, a 45 gripper for pulling an upper over a last, means for operating said gripper to pull the margin of the upper inwardly over the bottom of the last, and mechanism controlled by said 50 gripper-operating means for locking the gripper against movement in a direction away from the plane of the last bottom.

34. In a machine of the class described, a gripper and an upper-fastening device combined to move as a unit in pulling an upper 55 inwardly over an insole on a last, and automatic means for locking said gripper and fastening device against movement in a direction away from the plane of the last bottom in the upper-fastening operation.

35. In a machine of the class described, a 60 support having thereon a gripper and also a tack driver and operating means for said tack driver, means for moving said support to cause the gripper to pull the margin of an upper 65 per inwardly over an insole on a last, and

means for locking said support against movement in a direction away from the plane of the last bottom in the operation of the tack driver.

36. In a machine of the class described, the combination with means for pulling an upper over the forepart of a last, of additional upper-pulling means comprising a gripper arranged to operate upon the upper in a location substantially where the edge of the 75 shoe bottom curves inwardly toward the shank, operating means for moving said gripper initially widthwise of the last to pull the upper, said gripper being mounted to move automatically, in response to the resistance 80 encountered in pulling the upper, to place the upper upon the shoe bottom in position to be fastened, and upper-fastening means movable with said gripper into position to fasten the upper.

37. In a machine of the class described, grippers arranged to operate upon an upper respectively at opposite sides of a last in locations substantially where the edge of the last bottom curves inwardly toward the shank, 90 operating means for moving said grippers initially widthwise of the last to pull the upper, said grippers being mounted to move automatically, in response to resistance encountered in pulling the upper, to place the 95 upper upon the shoe bottom in position to be fastened, and means carried by said grippers for fastening the upper.

38. In a machine of the class described, grippers arranged to operate upon an upper 100 respectively at opposite sides of a last in locations substantially where the edge of the last bottom curves inwardly toward the shank, operating means for moving said grippers initially widthwise of the last to pull the 105 upper, said grippers being mounted to move also toward the plane of the shoe bottom, in response to resistance encountered in pulling the upper, to place the upper upon the shoe bottom in position to be fastened, and upper- 110 fastening devices arranged to be positioned relatively to the shoe bottom by the movement of the grippers.

39. In a machine of the class described, the combination with means for pulling an 115 upper over the forepart of a last, of additional upper-pulling means comprising grippers arranged to operate upon the upper in locations substantially where the edge of the shoe bottom curves inwardly toward the shank, said 120 grippers being movable automatically into positions determined by the particular shoe being operated upon to place the margin of the upper upon the shoe bottom in position to be fastened, and upper-fastening devices 125 arranged to be positioned relatively to the shoe by the movement of the grippers.

40. In a machine of the class described, the combination with means for pulling an upper over the forepart of a last, of additional up- 130

per-pulling means comprising grippers arranged to operate upon the upper in locations substantially where the edge of the shoe bottom curves inwardly toward the shank, and means for moving said grippers to pull the upper inwardly over the shoe bottom and for simultaneously imparting to them turning movements to position their jaws in approximately parallel relation to the adjacent portions of the inwardly curved edge of the shoe bottom.

41. In a machine of the class described, a gripper arranged to operate upon an upper in a location substantially where the edge of the shoe bottom curves inwardly toward the shank, and operating means for imparting to said gripper upper-pulling movement inwardly over the shoe bottom and for simultaneously turning it to position its jaws in approximately parallel relation to the adjacent portion of the edge of the shoe bottom.

42. In a machine of the class described, a gripper arranged to operate upon an upper in a location substantially where the edge of the shoe bottom curves inwardly toward the shank, said gripper being mounted for turning movement about an axis substantially perpendicular to the shoe bottom, and operating means for imparting to said gripper upper-pulling movement inwardly over the shoe bottom, said operating means being constructed and arranged to act automatically upon the gripper in its inward movement to turn it about its axis into a position approximately parallel to the adjacent portion of the edge of the shoe bottom.

43. In a machine of the class described, a gripper for pulling an upper over a last, said gripper being mounted for turning movement about an axis substantially perpendicular to the bottom of the last, and operating means for moving said gripper inwardly over the bottom of the last, said gripper having thereon a face engaged by said operating means and inclined to the direction of movement of said means to cause the gripper to be turned about its axis in its inward movement.

44. In a machine of the class described, a gripper for pulling an upper over a last, said gripper comprising an inner jaw and an outer jaw movable to pull the upper inwardly over the bottom of the last and mounted to turn about an axis substantially perpendicular to the bottom of the last, and operating means for engaging said outer jaw and thereby imparting inward movement to both the jaws, said outer jaw having a face engaged by said operating means and inclined to the direction of movement of said means to cause the jaws to be turned about their axis in their inward movement.

45. In a machine of the class described, a gripper for pulling an upper over a last, said

gripper comprising an outer jaw and an inner jaw movable to pull the upper inwardly over the bottom of the last, a spring arranged to act, when permitted, to move the outer jaw into gripping relation to the inner jaw, and operating means arranged to control the gripping movement of the outer jaw and to act thereafter to impart inward pulling movement to both jaws.

46. In a machine of the class described, a gripper for pulling an upper over a last, said gripper comprising an inner jaw and an outer jaw, means arranged to act through said outer jaw to impart inward movement over the bottom of the last to both the jaws and thereafter to retract the outer jaw from the inner jaw, and a device arranged to hold said inner jaw from retractive movement with the outer jaw.

47. In a machine of the class described, a gripper for pulling an upper over a last, said gripper comprising an inner jaw and an outer jaw, a spring tending to force said jaws toward each other, means arranged to act through said outer jaw to impart inward movement over the bottom of the last to both the jaws and thereafter to retract the outer jaw from the inner jaw, a device arranged to lock the inner jaw against outward movement when the outer jaw is retracted, and means for operating said device to release the inner jaw to permit it to be retracted by the spring.

48. In a machine of the class described, a gripper for pulling an upper over a last, said gripper comprising a pair of jaws one of which is movable toward and from the other, and upper-fastening mechanism including a driver for fastenings combined with said movable jaw to move therewith.

49. In a machine of the class described, a gripper for pulling an upper over a last, said gripper comprising an outer jaw movable toward and from an inner jaw and movable with the inner jaw about an axis substantially perpendicular to the shoe bottom, and upper-fastening means including a driver for fastenings movable as a unit with said outer jaw.

50. In a machine of the class described, a gripper and a fastening-inserting device movable as a unit inwardly over the bottom of a last to cause the gripper to pull an upper over the last, said fastening-inserting device comprising mechanism operative to insert a fastening in response to resistance of the upper to the pull of the gripper.

51. In a machine of the class described, a gripper and means for operating it to pull an upper inwardly over the bottom of a last, said operating means comprising parts relatively movable in response to resistance of the upper to the pull of the gripper, a fastening-inserting device including a driver movable with said gripper, and mechanism oper-

ative in response to the relative movement of said parts to cause the driver to drive a fastening.

52. In a machine of the class described, a gripper and means for operating it to pull an upper inwardly over the bottom of a last, said operating means comprising parts relatively movable in response to resistance of the upper to the pull of the gripper, a fastening-inserting device including a spring-oper-

ated driver and a latch for holding it in retracted position, and mechanism arranged to be operated by the relative movement of said parts to cause said latch to release the driver.

In testimony whereof we have signed our names to this specification.

JOSEPH GOULBOURN.

WILLIAM THOMAS BUCKINGHAM ROBERTS.
